UNITED STATES PATENT OFFICE.

PETER M. FRANZEN, OF CHICAGO, ILLINOIS.

FAN.

Application filed June 30, 1921. Serial No. 481,465.

To all whom it may concern:

Be it known that I, PETER M. FRANZEN, a citizen of the United States, and a resident of Chicago, Cook County, and State of Illinois, have invented certain new and useful Improvements in Fans, of which the following is declared to be a full, clear, and exact description.

This invention relates to fans and its principal object is to make a light, flexible and inexpensive fan which is attractive and suitable for advertising purposes and in which the handle portion may be used over and over again with various forms of fan body portions. Another object is to provide a fan which may be readily and quickly assembled and taken apart.

The invention consists in the several novel features hereinafter fully set forth and claimed.

The invention is clearly illustrated in the accompanying drawing in which Fig. 1 is a front view of the fan embodying a simple form of the present invention; Fig. 2 is a rear view thereof; Fig. 3 is a longitudinal section taken on the line 3—3 of Fig. 1; Fig. 4 is a cross-section taken on the line 4—4 of Fig. 1; Fig. 5 is a front elevation of a fragment of the handle portion; and Fig. 6 is a detail cross-section taken on the line 6—6 of Fig. 5.

Referring to said drawing, the reference character 10 designates the fan body portion, which may be of any suitable form and it is preferably made of a sheet of cardboard or other stiff paper. Along the median line of said fan body portion are formed two apertures 11 suitably spaced apart, as is clearly seen in Figs. 2 and 3, through which apertures is inserted one handle member 12 of the handle portion 13, part of said handle member 12 lying on one side or face *a* of the body portion 10 and the other part lying on the reverse or opposite face or side *b* thereof, as is indicated in Fig. 3. One end of the other handle member 12^a of the handle portion is secured to one end of the handle member 12 by a rivet pin or the like 14 and said handle member 12^a extends along the rear face *b* of the body portion 10 in close proximity thereto and is detachably secured at its other end to the handle member 12 by connecting means, here shown as comprising a headed pin 15 which enters a keyhole slot 16 formed in said handle member 12. The two handle mem-

bers 12, 12^a are substantially of the same length and comprise two thin strips of light gauge, flexible, sheet metal, and the pin 15 and keyhole slot 16 are so arranged with respect to each other that when the two handle members 12, 12^a are placed back to back, the headed pin 15 will be confined in the narrow part 17 of the keyhole slot 16, as is clearly illustrated in Fig. 5.

For the purpose of ornamenting the fan and otherwise making it attractive and suitable for advertising purposes, a sheet, card, or the like, 18, bearing a suitable picture or advertising matter, is pasted upon the front face *a* of the body 10 and is of sufficient size to cover the apertures 11 and the part of the handle member 12 which extends between said apertures 11. Said body 10 and sheet 18 form a sort of pocket 75 *c* for the reception of that portion of the handle member 12 which extends between the apertures 11. It is to be understood that the sheet or card 18 is pasted or otherwise secured to the face *a* of the body 10, 80 but the two are not pasted together along the place where the pocket *c* is formed.

The opposite side *b* of the fan body 10 may also have sheets or cards 19 bearing suitably ornamented surfaces or advertising matter, which may be pasted or otherwise secured to the face *b* of the fan body 10.

One of the particular advantages of this fan consists in the fact that the handle members are made of very light, flexible, gauge 90 sheet metal, which provides a thin flexible handle that takes but very little room and adds scarcely anything to the thickness of the fan body. Furthermore, the pin and keyhole slot connection between the two 95 handle members provides a simple but efficient means for quickly attaching the two handle members or detaching them from each other. In attaching the handle portion to the body, the handle member 12 is slipped 100 into the upper aperture 11 down through the pocket *c* and back through the lower aperture 11, and the headed pin 15 is inserted in the larger end of the keyhole slot 16 by flexing or bending the handle member 12^a as seen in dotted lines in Fig. 3, to bring the head of the headed pin 15 into said larger or round portion of the keyhole slot. Upon releasing the flexed handle member, it straightens out by reason of its own 110 elasticity and the head of the pin 15 is thereby brought into the narrow portion 17 of the

keyhole slot and the two handle members are thereby firmly but detachably secured together. The two handle members, when secured together, clasp the fan body between the apertures and firmly connect it with the handle. In case it becomes desirable to replace the fan body 10 with a different one, the two handle members are disconnected at their lower ends by flexing them and 10 withdrawing the pin from the larger portion of the keyhole slot and then withdrawing the handle member 12 from the pocket c. A different body may then be placed upon the handle, as before.

15 More or less variation of the exact details of construction is possible without departing from the spirit of this invention; I desire, therefore, not to limit myself to the exact form of the construction shown and described, but intend, in the following 20 claims, to point out all of the invention disclosed herein.

I claim as new and desire to secure by Letters Patent:

- 25 1. As a new article of manufacture, a fan comprising a fan body portion having an elongated pocket formed therein, and a handle portion formed of two thin flexible strips of sheet metal permanently secured 30 together at one end and detachably secured together at the other end by a headed pin and keyhole slot connection, one of said handle members extending through said pocket in the body portion.
- 35 2. As a new article of manufacture, a fan comprising a fan body portion formed with two spaced apertures, and a handle portion comprising two thin flexible sheet metal strips permanently secured together at one 40 end and having headed pin and keyhole slot connection at the other end, whereby said other ends may be detachably secured together, one of said handle members extending through said apertures in the body portion.
- 45 3. As a new article of manufacture, a fan

comprising a fan body portion having two spaced apertures formed therein and a sheet of material secured to one face of said fan body portion and covering said apertures, there being a pocket between said fan body portion and sheet extending between said apertures, and a handle portion formed of two thin flexible sheet metal strips permanently secured together at one end and having a headed pin and keyhole slot connection at the other end, whereby they are detachably secured together at said end, one of said handle members extending through said pocket in the body portion.

4. As a new article of manufacture, a fan comprising a fan body portion having two spaced apertures formed therein and a sheet of material secured to one face of said fan body portion and covering said apertures, 65 there being a pocket between said fan body portion and sheet extending between said apertures, and a handle portion formed of two thin flexible sheet metal strips permanently secured together at one end and detachably secured together at the other end, one of said handle members extending through said pocket in the body portion and its end portions extending out through said apertures.

5. As a new article of manufacture, a fan comprising a fan body portion having two widely spaced apertures formed therein and a sheet of material secured to one face of said fan body portion and covering said apertures, there being an elongated pocket between said fan body portion and sheet extending between said apertures, and a handle portion removably secured in said pocket, and having a part extending out through one aperture, and another part extending out through the other aperture and projecting beyond the body portion, said handle portion having means for clamping it against a wall of said pocket.

PETER M. FRANZEN.
